UNITED STATES PATENT OFFICE

HENRY PRICE BALL, OF BROOKLYN, NEW YORK

REPRODUCING MUSICAL INSTRUMENT

Original application filed February 5, 1924, Serial No. 690,756. Divided and this application filed October 9, 1926. Serial No. 140,619.

This invention relates to means for reproducing music as originally played by the artist on the piano.

The objects of my invention are as follows:

1. To provide a reproducing piano that will respond to my special records and give an infinite variety to the changes of intensity of the tones produced instead of a limited number of changes thereof as at present in existing instruments.

2. To provide a reproducing piano to operate with a single pressure in the wind chest, and that a comparatively high pressure, thereby simplifying the pumping mechanism and overcoming the present troubles when playing soft passages, more especially found in old instruments and in both new and old instruments in damp weather.

20 Also my invention has other objects either to be enumerated hereinafter or which will be apparent to those skilled in the art from an understanding of the following specification in connection with the drawings.

25 This case is a division based on my original United States patent application filed February 5, 1924, which resulted in Patent No. 1,716,811, June 11, 1929.

Referring to the drawings, Fig. 1 is a view 30 partly in section of an upright reproducing piano embodying my invention, in which I have also included the recording attachment showing how the same is applied to an upright piano as distinguished from a grand piano; Fig. 2 is a detail in section of a pneumatic valve and wind chests; Fig. 3 is a detail; and Fig. 4 is a view of the perforated record.

Referring to Fig. 1, the casing forming 40 the front 159 of the piano is provided with a music roll box 157 having mounted therein the tracker board 40 with a single row of tracker ducts 41. Suitable bearings not shown are provided to support and drive 45 the music roll spool 241, and take up spool 156. As the music sheet 22 passes over the tracker board, the perforations therein permit air to enter the tracker ducts 41. This air is conducted through tubes 42 to the valve 50 boxes 43. The valve box 43 comprises the

wind chests 44 and 45 which run the entire length of the piano action, the air of which is partly exhausted. In my preferred form I employ a single pressure at all times in the wind chests, which will be designated as high pressure, to distinguish it from other systems on the market which use a variable pressure ranging from a high pressure to a low pressure. I may operate wind chests 44 and 45 at different pressures in order to adapt the valve box 43 to respond to music rolls other than those made by my system. For example, I might have a permanently maintained high pressure in the wind chest 44, and a variable pressure in wind chest 45. The air pressure in the wind chest 45 being raised and lowered by any of the well known means now employed in player pianos on the market, to increase or lower the pressure in the wind chest 45 in accordance with the intensities of the tones produced. A variable pressure in the wind chest is almost universally used today as a means of changing the force of attack of the pneumatic action. As distinguished from this, my system employs 60 but a single pressure in the wind chests, and the degree of attack is accomplished by my method of operation which will now be described.

The pneumatic action is divided into three sections as shown in Fig. 1; each section is provided with a series of striker pneumatics 46 and is adapted to raise the wippen standard 3 corresponding to the string to be struck. The striker pneumatic 46 (one for each tone) is provided with a finger 47, secured thereto, and which engages with the underside of a lug 48 secured to the wippen standard 3 in such a way that any striker pneumatic 46 can operate without interference with any other. Each striker pneumatic 46 is in communication with an upwardly extending duct to a valve comprising a hollow cylindrical member or sleeve 49 in which a plug 50 is vertically movable. The plug 50 is provided centrally with a pin 51 finding a bearing in a spider 52 at the lower end of the valve. The plug 50 is provided on its upper end with a pin 51 passing through a hole in the upper part of the valve 100

box to the outside and is provided with two heads 52 and 53 whereby it can be moved vertically so that the plug 50 can be caused to enter to a greater or less extent the hollow cylinder 49. On the top of the valve box 43 I provide a control pneumatic 54 somewhat similar in its construction to the striker pneumatic 46 but smaller in size. This control pneumatic has attached to it the arm 55 which engages with the heads 52 and 53 of the pin 51. A spring 56 tends at all times to hold the valve plug 50 in its uppermost position.

Mounted in the valve box 43 are two valves 57 and 58 of the usual inside type. These valves are provided with pins 59 and 60 respectively, the lower ends of which are headed and bear against flexible discs 61 and 62, respectively. The pins 59 and 60 are provided with spider bearings, not shown, in which they are free to move vertically, and which maintain the valves 57 and 58 respectively, in their central relation as regards the valve seats. The valve 57 controls the passage 63 which communicates to the wind chest 44 through port 165 and the outside air through port 64. The valve 58 controls the communication of passage 65 with the outside air through port 66 and to the wind chest 45 through port 67. The passage 65 is in communication with the striker pneumatic 46 through valve plug 50. Directly below the valve 57 I provide two discs 68 and 69. These discs are secured to the valve box at their periphery, similarly to the discs 61 and 62, so that they are free to move at the center. The space 170 between these discs is in direct communication with the passage 63. The surface under each of the discs 68 and 69 is preferably curved as shown in Fig. 2. The passage 63 is in connection with the control pneumatic 54, through port 70, controlled by the valve 71, chamber 72, the port 73 controlled by a flap valve 74 which acts as a check preventing the flow of air from leaving the control pneumatic 54 excepting through the bleed hole 75 in a plate secured to the upper part of the valve 74. This valve 74 is held in place at one side as shown so that it is free to lift off its seat, but not, however, with enough freedom to become displaced. The valve 71 is provided with a headed pin 76 acted upon by the disc 77. The underside of the valve box 43 is provided with a valve 78 which controls the air to a passage 79 running from the outside of the box to the underside of disc 68. The valve 78 is provided with a resilient arm 80 secured to the underside of the valve box 43 at one end by screws 81. The free end 82 is pressed down by the striker pneumatic 46 when in its extreme low position, as shown in Fig. 2. The passage 79 is closed upon the striker pneumatic passing through its initial movement.

65 The valve box 43 is provided with a duct 83

to which the tube 42 (Fig. 2) communicates to the tracker ducts 41. This passage 83 connects to the underside of the disc 69 and also communicates through a passage 84 to the space under the disc 61. In this passage 70 84 I provide a check valve 85 which permits air to pass upwardly but not downwardly. I provide the passage 86 running from the underside of disc 69 to the space under the disc 62, likewise the passage 87 running from the space under the disc 61 to the underside of the disc 68. The space under the discs 61 and 62 is connected to wind chests 44 and 45 through bleedholes 88 and 89 respectively. The space under the disc 77 is connected by 80 passage 90 to passage 65. The operation of this portion of my device will now be described. As the music sheet 22 passes over the face of the tracker board 40, the perforations in the music sheet open the ends 85 of the tracker board ducts 41 to the outside air. If a perforation such as 34 (Fig. 4) is preceded by a small hole 33 representing a soft tone, then there are two successive impulses of air passing into the tracker duct and through the tubular connection 42 into the valve box. Whereas, if the tones are to speak very loud, there is but a single impulse of air permitted to enter the tracker duct through a perforation in the music sheet 22, such as the perforation 115, which is not preceded by a small hole. The degree of loudness or softness of each tone is controlled by the distance between the note perforation and the small hole, as fully explained in my co-pending case Serial No. 140,620, filed Oct. 9, 1926. It has been seen that the valve box comprises two valves 57 and 58 which control the pressure of air in the passages 63 and 65 respectively. Normally, these two valves are in 100 their lower position, and passages 63 and 65 are connected to the outside air and, therefore, are at atmospheric pressure. Normally, the ducts 86 and 84, as well as the ducts 83 and 87 and their connection 42 to the tracker board 40, have all been partly exhausted through the bleedholes 88 and 89 to the pressure of the wind chests 44 and 45. The flexible disc 68 is, therefore, under these conditions held in its upper position, as shown in 105 Fig. 2, due to having atmospheric pressure on the underside and pressure corresponding to that of the wind chest on the upper side. Likewise, the flexible disc 69 is held in its lower position by reason of having atmospheric pressure in space 70 above, and the lower pressure corresponding to that in the wind chests 44 and 45 beneath it. In these 110 normal positions, the space under the flexible disc 61 is shut off from the outside air through duct 79 and the disc 69 in the normal position prevents air from the tracker board passing directly through duct 86 to the space under the disc 62. Running from the space 115 under the disc 77 to the passage 65, the duct 120

90 provides air at atmospheric pressure to the underside of the disc 77, as valve 58 is in its lower position. The upper side of the disc 77 is exposed to the passage 63, having air also at atmospheric pressure, so that the normal position of this disc is down, as shown in Fig. 2. It will be observed that Fig. 2 shows all of the parts in their normally inactive position,—that is, in the position when they are not called upon to operate the piano action to produce musical tones.

Let us assume that a small hole 33 passes over the tracker board and opens one of the ducts 41 therein for a very short period of time, remembering that the small hole 33 is much smaller in diameter than the note perforation 34, and the amount of air that is permitted to pass into the tracker board and down into the valve box is thereby limited, and, therefore, can only do a certain amount of work. This feature is an important one as will be brought out. The small hole 33 permits air to pass through the tubular connection 42, down into the duct 83, under the check valve 85, which it raises and passes into duct 84, and then under the flexible disc 61. As the upperside of the disc has been partly exhausted, the atmospheric pressure underneath raises it, and also valve 57, thereby closing the port 64 to the outside air and opening the port 165 to the wind chest 44, thereby reducing the pressure in the passages 63 and 170 to that of the wind chests. As this takes place, the disc 77 raises by reason of the greater pressure on the underside, throwing the chamber 72 into communication with the passage 63, thereby causing the air in the control pneumatic 54 to be slowly reduced by passing through the bleed hole 75, port 70, passage 63, and port 165 into the wind chest 44. This reduction of the pressure of air in the control pneumatic 54 continues as long as these conditions exist. As the air in the control pneumatic 54 is drawn through the bleed hole 75, the upper movable member of the pneumatic moves slowly downwardly, carrying with it the valve plug 50 against the resistance of the spring 56. If, however, at any time during the downward movement of the upper portion of the control pneumatic 54, valve 58 is caused to move upwardly, the wind chest 45 is connected with the passages 65 and 90, the latter communicating with the space under the pouch 77, the pressure in duct 90 will become that of the wind chest 45, which is the same as the wind chest 44, and the pressure above and below the disc 77 will thus become the same. The valve 71 will drop, thereby causing a cessation of the passage of the air through the bleed hole 75 and the movable member of this control pneumatic 54 will become stationary, and likewise the movable element 50 of the valve

controlling the flow of air to the striker pneumatic 46.

In the normal position of the parts shown in Fig. 2, when the striker pneumatic 46 is in the position shown, the valve 78 maintains the ducts 79 open to atmospheric pressure, so that when valve 57 moves upward, it throws the partly exhausted air into the space 70, and the disc 68 moves downwardly; the outside air at atmospheric pressure has direct access through ducts 79 and 87 to the underside of the disc 61, and the valve 57 is thereby maintained in its upward position, irrespective of the fact that the small hole 33 may have passed over the tracker duct 41, and thereby closed it. The valve 57 is maintained in this upward position until the note perforation 34 or 36 has passed over the tracker duct, as will be explained later. Upon the opening of the tracker duct 41 by the note perforation 34, a greater amount of air is permitted to enter the valve box through connection 42 than when the small hole 33 opens the tracker duct. This air passes through the duct 83, under the flexible disc 69, causing it to move upwardly, thereby permitting the air at atmospheric pressure to pass through duct 86 to the underside of valve controlling disc 62, so that the valve 58 is moved upwardly, disconnecting the outside air from passage 65, throwing it onto the partly exhausted air of the wind chest 45. The air passes from the striker pneumatic 46, through the passage 49, passage 65, port 67, into the wind chest 45, at the same time communication is made between the wind chest 45 and the underside of disc 77, as explained above. As valve 58, therefore, moves upwardly, it causes immediate cessation of the downward movement of valve plug 50, and the striker pneumatic 46 is caused to move the finger 47 upwardly, bringing it against the lug 48 on the wippen upright, thereby throwing the piano action into action and causing the note to be struck. The degree of intensity with which the note is struck depends upon the position of the valve parts 49 and 50. If the moving member 50 of the valve is in the position shown in Fig. 3, it offers slight resistance to the passage of air from the striker pneumatic to the wind chest 45, and in this position the note is struck loud on the piano. As the valve plug 50 moves downwardly into various positions in the sleeve 49, it offers greater resistance to this flow of air; as a result of this, the striker pneumatic 46 actuates the piano action with decreasing energy until the position is reached when the valve plug 50 is in its lowest position in the sleeve 49, at which time the softest tone is struck on the piano. It is readily seen that an infinite variety of changes in the intensity of tone are produced by this method. In Fig. 2 I show

130

the valve parts as slightly conical. The movable member 50 of the valve is shown as a truncated cone, while the opening in the sleeve 49 is shown as conforming to the taper of the part 50. I wish it distinctly understood that I do not limit myself to the form of these parts shown, as I may utilize various forms to produce different effects. I find from experiment that the successful operation of these valve parts depends largely on the length of travel of the valve plug 50 in the sleeve 49. I, therefore, make these parts as long as possible in a longitudinal direction. The initial movement upwardly of the striker pneumatic 46 permits the valve 78 to close the duct 79 to the outside air, so that the upper position of the valve 57 at this time depends solely upon the air entering the ducts 83 and 84, through the note perforation in the music sheet. As both the valves 57 and 58 are now directly controlled by the note perforation, as soon as this perforation passes over the tracker duct 41, these two valves 57 and 58 drop, thereby causing the pneumatic 46 to assume its original position, as shown in Fig. 2, and the control pneumatic 54 raises quickly to its upward position, as shown in Fig. 2, by reason of the spring 56 carrying with it the movable valve member 50. The flexible flap valve 74 raises off its seat at this time, permitting the free flow of air into the control pneumatic through port 64, passage 63, port 70, chamber 72, port 73. The bleedholes 88 and 89 operate in the usual manner, to equalize the pressure above and below the disc 61 and 62 and as this takes place the discs 68 and 69 are seated by reason of the greater pressure on the outside, and the pressure under the disc, caused by the evacuation of the ducts 87 and 86 communicating with the underside of discs 61 and 62 respectively and which are evacuated as described. The necessity for the use of the check valve 85 which permits the flow of air in an upward direction only is on account of the fact that if this check valve were not employed, the air at atmospheric pressure entering passage 79 and communicating to the underside of disc 61 upon the opening of the tracker duct by the small hole 33, would find a direct path through ducts 84, 83, and 86, thereby operate the disc 62 and raise the valve 58, causing the tone to respond to the small perforation 33, instead of to the large perforation 34, as intended. An explanation of this is that as soon as the air pressure passes through duct 83 and under the flexible disc 69 and over the flexible disc 68, there being at this time less pressure in passage 70, both the disc 68 and the disc 69 would be moved off their seats and throw the ducts 79, 87, 84, 83 and 86 all into direct communication with each other, thereby defeating the objects of the

invention. The valve 58 must not operate until the note perforation 34 opens the tracker duct. In other words, the valve 57 operates in response to the opening of the tracker duct by the small hole 33, and the valve 58 responds to the opening of the tracker duct by the note perforation 34, and there must be a time interval between the operation of these two valves, excepting in loud notes, equal to the time interval between the opening of the tracker duct 41 and the small perforation 33 and the large perforation 34. In the case of a loud note 115, for example, all of the parts described above operate simultaneously,—that is, there is no time lag between the operation of valves 57 and 58, and the control pneumatic 54, therefore, in this case does not move downwardly, and a free passage is maintained between the striker pneumatic 46 and the wind chest 45, so that the maximum intensity of tone is produced.

It will be seen from the foregoing description that I have devised an extremely sensitive and accurate method of recording the notes selected by the performer as to their tempo, duration, phrasing and individual intensities; in fact, my record is a complete one in every detail of the performance as played. Further, that this record can be used immediately after being produced, to reproduce the musical composition as played by the performer.

In order to get greater precision in the time of operation of the control pneumatic 54 in its adjusting the throttling valve plug 50 described in connection with the form shown in Fig. 2, I would refer to Fig. 3. In this construction I provide a mechanically driven timing shaft 141, provided with ratchet wheels 155 or their equivalent, adapted to be engaged by pawls 142, there being one pawl and one wheel for each striker pneumatic. The pawl 142 is pivoted to the end of the arm 55, secured to the control pneumatic 54, and is normally held in relation thereto, by a stop 143 and a spring 151 as shown. The pawl is provided with a pin 150 which engages with the cammed end of a longitudinally movable vertical rod 144 having bearings 147 and 148 secured to the end of the valve box 143. The lower end of the rod 144 is provided with a collar 146, against which bears a spiral spring 145 tending to hold the rod in its lower position. A similar collar 152 locates the lower position of the rod 144. When in its lower position the end of the rod 144 passes to one side of the striker pneumatic 46, and is adapted to engage the projection 153 forming part of the movable member of the striker pneumatic 46. The shaft 141 may be geared directly to the driving mechanism in any well known manner, not shown, causing the paper 22 to travel over the tracker board 40, and is so timed that it moves at

about 45 degrees, during the time that it takes the paper 22 to travel the maximum distance between the small perforations 33 and the large perforations 34 in the music sheet. The

5 lower end of the pawl 142 is normally out of engagement with, but close to the teeth on the ratchet wheel 140.

The operation of this feature of my de- 10 vice will now be readily understood. As soon

as the control pneumatic 54 moves downward- 15 ly, the pawl 142 engages one of the teeth of the ratchet wheel 155 and as in this event the bleed hole 75 is adjusted so that the control pneumatic 54 will move down faster than

20 the wheel 155 will permit, the downward movement of the control pneumatic is retarded, and made to conform to the speed of the wheel 155 and its motion is, therefore, me- 25 chanically timed to the movement of the

25 music sheet 22, in its travel over the tracker board 40. As the note is struck by the striker pneumatic 46, the projection 153 comes against the lower end of the rod 144 causing its cammed upper end to engage with the 30 pin 150, thereby throwing the pawl 142 out of engagement with the teeth on the wheel 155, thereby overcoming the objection of having the teeth of the wheel 155 bear against the pawl 142 when the latter is stationary.

35 This prevents unnecessary noise and wear on the parts. This method of mechanically timing the movements of the parts is a refinement which in ordinary practice may not always be required. It is shown to disclose 40 one method of timing the movements of parts mechanically, to govern accurately their time of operation.

Having now described my invention so that anyone skilled in the art to which it 45 pertains can make and use the same, and having shown one embodiment of the same in accordance with the statutes, what I claim and wish to cover by Letters Patent is the following:

45 1. In an automatic piano player action, a wind chest, a striker pneumatic, a controlling valve, a throttling valve between the striker pneumatic and the controlling valve, and means for automatically setting the throttling valve before the striker pneumatic operates.

50 2. In an automatic piano player action, a striker pneumatic, a valve controlling the same, a throttling valve between the striker pneumatic and the controlling valve, and means for automatically setting the throttling valve before the striker pneumatic operates, and means adapted to lock the throttling valve in position during the operation of the striker pneumatic.

55 3. In an automatic piano player action, a wind chest, a striker pneumatic, a valve, a communication between the wind chest and the striker pneumatic controlled by the said valve, automatic means adapted to restrain

the flow of the air from the striker pneumatic to the wind chest, and means for adjusting the automatic means prior to the operation of the striker pneumatic.

4. In an automatic player piano action, a 70 striker pneumatic, a wind chest having a single fixed pressure of air, a passage leading from the wind chest to the striker pneumatic, a valve in said passage adapted to throw the striker pneumatic in and out of communication with the wind chest, and adjustable means adapted to be automatically set prior to the action of the striker pneumatic and to control the force of said action.

5. In a player piano controlled by a music 80 sheet, a striker pneumatic, a valve controlling the latter, means graduating the pressure of air supplied the pneumatic and automatic means adapted to preset the pressure graduating means under the control of the music- 85 roll prior to the operation of the valve.

6. The herein described method of automatically playing the piano which consists in selecting the note to be played, causing a period of time to lapse before playing the 90 note, proportional to the intensity with which the note is to be played and then playing the note at the predetermined intensity.

7. A piano player controlled by a music 95 sheet comprising a striker pneumatic, a valve controlling the pneumatic, and a separate pressure controlling means under the control of the sheet for each valve adapted to graduate the pressure of air to which the pneumatic responds.

8. In a player piano, a series of striker 100 pneumatics, a series of valves, a series of pressure regulating devices, one for each pneumatic, and an automatic presetting means for each device adapted to select the pressure of air to which the pneumatic responds.

9. In a player piano, a series of striker 105 pneumatics, a series of valves, a series of pressure regulating devices, one for each pneumatic, and an automatic presetting means for each device adapted to select the pressure of air to which the pneumatic responds before the pneumatic is called upon to act.

10. In a player piano controlled by a music 110 sheet, a series of strikers and a series of valves, a pressure regulator for each striker and a mechanically driven selecting device adapted to set the pressure regulator individually 115 for each striker.

11. A player piano, controlled by a music 120 sheet having a note hole and a pilot hole for each tone, comprising means for striking a tone responsive to the note hole and means adapted to vary the intensity of the tone according to the various relative positions between the note hole and pilot hole.

12. A player piano, controlled by a music 125 sheet in which each tone is represented by a 130

pair of holes spaced different distances apart, a tone hole and an intensity hole, comprising a tone producing device responsive to the tone hole, and an intensity modifying device responsive to the intensity hole and adapted to graduate the intensity of the tone in proportion to the graduated distance between the holes in each pair.

13. The herein described method of automatically selecting and playing a plurality of notes in a chord which consists of selecting each note to be played, in advance of the time of playing, a period of time proportional to the desired intensity of its tone and then playing all the notes simultaneously.

14. The herein described method of automatically playing musical notes which consist in selecting the notes to be played and causing periods of time to lapse subsequently to the selection of the notes and before the playing of the notes proportional to the respective intensities of the notes.

15. In a player piano responsive to a music sheet, a wind chest having a single fixed pressure, a striker, a valve for the striker and means under the control of the music sheet adapted to vary the blow of the striker independent of the amount of air pressure in the wind chest.

16. In a player piano, means for playing a group of notes simultaneously in a chord and automatic means adapted to select the individual intensities with which each note is to sound.

17. In a player piano controlled by a music sheet, means for playing a group of notes simultaneously in a chord and automatic means responsive to the music sheet adapted to select the individual intensities with which each note is to sound.

Signed at New York in the county of New York and State of New York this 8th day of October, A. D. 1926.
